UNITED STATES PATENT OFFICE.

GONSHIRO KUBOTA, OF MINAMI-KU, OSAKA, JAPAN.

APPARATUS FOR CASTING CAST-IRON PIPES.

Application filed December 13, 1922. Serial No. 606,588.

This invention relates to improvements in apparatus for casting iron pipes, the object of the invention being to provide a metallic mold for this purpose, in which provision is made for longitudinal expansion of the mold, the construction of which is such that the heat of the molten metal is not absorbed and any deformations of the mold due to the high temperature to which it is subjected can be readily corrected.

With the foregoing and other objects in view, which will appear as the description proceeds, the invention consists in the novel features of construction and combination of parts which will be more fully described hereinafter and particularly pointed out in the claim.

In the drawings accompanying and forming part of this specification—

20 Fig. 1 is a partly sectional side elevation of the assembled mold;

Fig. 2 is a side view of the upper part of the mold illustrating a form of means for suspending said mold;

25 Fig. 3 is a perspective view of a portion of the mold showing a detail of construction; and

Fig. 4 is a sectional plan view taken on the line IV—IV of Fig. 1.

30 The same characters of reference designate the same parts in the different figures of the drawings.

It is well known that molds heretofore used for casting elongated objects, such as 35 iron pipes, were made of sand. So far as I am aware, metallic molds have never been used for this purpose, for the reason that the mold would quickly absorb the heat of the molten metal that was poured into it and thus chill the surface of the cast pipe and 40 make it rough. Furthermore, the expansion and contraction of the metallic molds did not coincide with those of the congealing metal poured into the molds, and consequently the pipe cast in the mold was apt to 45 crack while cooling down. Moreover, metallic molds easily become deformed owing to the excessive temperature to which they are subjected during the casting operation, such deformation being especially noticeable in a long mold such as is necessary for casting pipes, and consequently a metallic mold could not be used for continuous casting.

50 All of the disadvantages above referred to are eliminated by the use of metallic molds

of the special construction forming the subject-matter of this application.

Referring to the drawings, the mold comprises two half sections *a* and *b* respectively, which when brought together form a complete mold having a cylindrical inner wall, the diameter of the mold corresponding to the external diameter of the article which it is desired to cast. The sections *a* and *b* of the mold are preferably provided with 60 comparatively thin walls, for instance, for casting a pipe of 80 m. m. inner diameter and 4 metres in length, the thickness of the walls of the mold sections should be approximately 20 m. m. By reason of this construction, any deformation of the mold due to high temperature is readily corrected by means of a comparatively slight exterior pressure or stress.

For supporting the mold during operation, I have provided a pair of base plates *g* and *h* respectively, shown in dotted lines in Fig. 1. Secured to the plate *g* are a plurality of guide blocks *c* and *d*, and carried by the plate *h* are a plurality of blocks *c'* and *d'*, for retaining and guiding the sections of the mold in the manner hereinafter described. The guide blocks *c* and *c'* are each provided with a longitudinal slot, preferably of dove-tail formed in cross-section, 75 while the sections *a* and *b* have formed thereon a plurality of projections *e* also of dove-tail form and adapted to slidably fit the slots in the guide members *c* and *c'*, as clearly shown in Fig. 4. The guide blocks *d* and *d'* are also each provided with a longitudinal slot, which, however, is preferably of 80 rectangular form in cross-section, while the sections *a* and *b* are provided with projections *f* adapted to slidably fit said slots. 90 The projections *e* and *f* of the mold sections are in axial alinement, and are connected by longitudinal ribs *z*.

Each of the mold sections *a* and *b* is provided near one end thereof and beyond the outermost projection *e*, with a projection *m* having longitudinally inclined or tapered sides, the larger ends of which are wider than the adjacent projections *e* so that the projections *m* will not pass through the slots in the guide members *c* and *c'*, whereby when the mold is assembled in vertical position as shown in Fig. 1 it will be prevented from sliding downwardly out of its guide members by the engagement of the shoul- 100 105 110

ders formed on the projections *m* with the ends of the uppermost guide members *c* and *c'*. By reason of this construction the mold sections are free to expand and contact longitudinally.

Each of the guide blocks *c'* and *d'* is provided with a pair of curved wings *i* adapted to embrace the mold section *b*, the distance between the wings *i* being such that the longitudinal flanges of the mold sections snugly fit therebetween, as shown in Fig. 4, whereby the lateral displacement of the mold sections relatively to each other is prevented. The mold sections are each further provided with a pair of wedge-shaped lugs or projections *j*, one at each side thereof, said lugs being disposed upon the longitudinal edges of the flanges of the mold sections, as shown in Fig. 3. The angle and position of the lugs *j* are such that when the mold sections *a* and *b* are brought into contiguous relation the lugs of one section will engage with and lie upon the lugs of the other section, as shown clearly in Fig. 1, whereby the sections *a* and *b* are maintained in correct longitudinal position relative to each other.

The operation of the apparatus is as follows: One of the base plates, for instance, the plate *g*, is secured to a fixed support, such as a rigid vertical wall, while the other plate *h* may be mounted on the ram of a hydraulic press and is moved toward and from the mold section *a* during the operation of the press. When a casting is to be made, the sections *a* and *b* are first separated sufficiently far apart to permit a core which has been prepared for the purpose, to be placed between said sections, whereupon the movable section *b* is moved by means of the ram or other apparatus into engagement with the section *a*. The core 10 herein shown comprises a metallic tube having a number of perforations, said tube being provided with a covering or casing of sand. The core, however, forms no part of the present invention, and may be made in any well-known manner. The ram or other operating mechanism is advanced sufficiently to bring the longitudinal flanges of the section *b* into close contact with those of the section *a*, so that the longitudinal flanges of both sections will lie between the wings *i* of the guide members *c'* and *d'*. During this operation, the wedge-shaped lugs *j* will have come into contact with each other and will act to prevent any longitudinal displacement of one section relatively to the other. At the same time, the bottom flanges of the mold section and projections *o* (shown in dotted lines at the

upper end of Fig. 1) act to center the core *n* and retain it in proper position during the casting operation. The mold is then heated to the proper temperature and molten metal is poured thereinto.

As hereinbefore stated, the thickness of the mold is very small compared with the size of the pipe to be cast, and consequently the temperature of the mold will quickly rise to a point near to that of the molten metal, so that very little heat will be absorbed by the mold. As soon as the cast pipe begins to contract the mold section *b* is backed away from the section *a*, whereby the cast pipe may be removed and permitted to freely contract. The mold, having been heated by the molten metal to a high temperature, will probably be somewhat deformed or distorted. Owing, however, to the fact that the wall is comparatively thin, the pressure necessary to again bring the mold section into contiguous relation will correct the deformation, such correction being aided by the guiding elements hereinbefore described. While I have described and illustrated a mold divided into two sections, one being maintained in fixed position and the other movable toward and from the fixed section, it is obvious that for casting pipes of large diameter, the mold may be divided into three or more sections, one being fixed and the others movable toward and from said fixed section. It is, therefore, to be understood that I do not limit my invention to the precise features of construction herein shown, as I am aware that many mechanical changes and modifications may be made therein without departing from the spirit and scope of the invention as pointed out in the claim hereto appended.

Having thus described my invention, what I claim is:

A metallic mold for casting iron pipe, comprising a pair of elongated mold sections, fixed guide blocks for supporting one of said sections for slidable movement longitudinally, guide blocks movable toward and from said section and adapted to support the other section for slidable movement longitudinally, a pair of wings carried by said movable guide blocks and adapted to engage said first section thereby to prevent lateral displacement of the sections, and wedge-shaped projections carried by said sections and adapted to be brought into cooperative engagement thereby to prevent longitudinal displacement of the sections.

In testimony whereof I have signed my name to this specification.

GONSHIRO KUBOTA.
